UNITED STATES PATENT OFFICE.

DANIEL E. SEDLACK, OF NEWARK, NEW JERSEY.

BAG LOCK.

Application filed January 12, 1924. Serial No. 685,749.

To all whom it may concern:

Be it known that I, DANIEL E. SEDLACK, a citizen of the United States, residing at Newark, in the county of Essex and State 5 of New Jersey, have invented certain new and useful Improvements in Bag Locks; and I do hereby declare the following to be a full, clear, and exact description of the invention, such as will enable others 10 skilled in the art to which it appertains to make and use the same.

The invention relates to improvements in locks for traveling bags and the like and has for its object to provide a simple 15 and efficient form of lock that may be operated only by a specific form of key, especially fitted to the individual lock, and thereby overcome the salient objection to bag locks of the ordinary type, which are 20 capable of being operated by a common key, and in many cases by means of a bent wire or similar implement, and are, therefore, of little protective value. To this 25 end, the instant invention comprises a casing adapted to be secured to one of the bag frame members, said casing containing a sliding latch cooperating with the usual hasp attached to the other bag frame member, the latch being held normally in hasp 30 engaging position by means of supporting springs, and forced out of hasp engaging position by means of a sliding finger piece which also contains a key hole, the latch 35 cooperating with a sliding bolt provided with shoulders adapted to be moved into and out of registry with cooperating shoulders on the latch to lock the same against movement, the locking and unlocking movements of the bolt being effected 40 by a tumbler slidably mounted on the latch, which tumbler is associated with a catch pivoted to the latch, the tumbler and catch being provided with key engaging surfaces so disposed that the catch must be operated 45 by the key to release the tumbler, which latter is then actuated by the further movement of the key to shift the bolt to either the locking or unlocking position with respect to the latch. By appropriately designing and arranging the key engaging surfaces of the tumbler and the catch, it 50 will be apparent the lock can be operated only by a key provided with a special form of bit, so that each lock will have its distinctive key and cannot ordinarily be

operated by other means or other keys having differently fashioned bits.

The invention is illustrated in the accompanying drawings in which:

Fig. 1 is a fragmentary plan view of a traveling bag having the improved lock applied thereto.

Fig. 2 is a side elevation of the lock viewed from the open side thereof.

Fig. 3 is a vertical section on the line 3-3 of Fig. 2, showing the lock applied to the cooperating element of the bag frame.

Fig. 4 is a plan view of the lock with the top plate removed.

Fig. 5 is a longitudinal horizontal section 70 through the lock.

Fig. 6 is a perspective view of the bolt.

Fig. 7 is a perspective view of the tumbler for operating the bolt.

Fig. 8 illustrates a key adapted to operate 75 the particular lock.

Referring to the drawings, 1 indicates the jaw frame member of a traveling bag to which the lock is secured and 2 the mating bag frame section which carries the usual 80 construction of hasp 3 which cooperates with the latch member of the lock to hold the bag in closed relation.

The lock proper comprises a casing 10 having a bottom, a front wall and end 85 walls, the latter being provided with the usual perforated flanges 11, by means of which the casing is secured to the appropriate bag frame member by rivets, with the open side of the casing adjacent the flat surface of the bag frame, as will be understood. The front wall of the casing is provided with two spaced openings to receive the two members of the hasp secured to the other frame member of the bag. The top of the casing is closed by means of a plate 13, having notches in its ends to receive lugs 14 on the end walls of the casing which are bent over the top of the plate 13 to secure the latter in position.

Secured to the bottom of the casing and the top plate 13 are guide pins 16, located at opposite ends of the casings, and upon said guide pins is slidably mounted a latch 105 20 having hasp engaging lugs 22 struck upward therefrom, so as to project normally into the path of movement of the hasp members 3-3 when the latter are passed through the openings 12 in the front wall 110

of the casing, each hasp member 3 having the usual opening 4 with which the corresponding lug 22 cooperates.

Formed centrally of the top plate 13 of the casing is a guide flange 17, generally elliptical in shape, which defines the opening through which reciprocates the usual form of hollow push button or finger piece 23 which is provided on its lower portion with two leg sections 24-24, which are passed through spaced openings 21-21 in the flat body portion of the latch 20 and upset to secure the finger piece rigidly to the latch. The top of the finger piece 23 is provided with a key hole slot 27, the center of which is in alignment with a key post 26 which is secured at its lower end in the bottom of the casing and extends upwardly through the lock to a point just below the top of the finger piece, so that the barrel of the operating key may be readily engaged with the post and the key accurately guided to its operating seat.

Secured to the ends of the latch plate 20, by means of lugs 31 engaging notches 23 in the ends of the latch plate, is an auxiliary casing 30 having a bottom plate perforated to receive the guide pins 16 and the key pin 26, said casing being cut away along its edge adjacent the front wall of the main casing 10, the rear wall of the casing being cut away at its mid section to provide an opening 34. Secured to the bottom of the auxiliary casing 30 are two studs or pins 35 spaced at equal distances from the center of the casing, which serve as guides for a tumbler 40, comprising a section stamped from sheet metal provided with slots 41-41 through which the pins 35 project to guide the tumbler in its sliding movement on the bottom of the auxiliary casing 30. The rear edge of the tumbler has a longitudinal projection 43 which extends into the opening in the rear wall of the casing 30 and serves as a stop to limit the extent of the sliding movement of the tumbler in the casing. Formed on the front edge of the tumbler 40 are two spaced lugs 42-42, adapted to engage the locking bolt which will be hereinafter more particularly described. The mid section of the tumbler is excised, as at 44, to permit the rotation of the key and the inner portion of the recess 44 is shouldered, as at 45, to provide an engaging surface for the lower section of the key bit, by means of which the tumbler is slid or reciprocated on the bottom auxiliary casing 30. On the upper face of the tumbler, there is formed or secured an upstanding lug 46 having one vertical face rounded.

Superposed on the tumbler 40 and mounted for pivotal movement on the pin 35 remote from the lug 46, is a catch 50 having its forward edge formed on a curve 51, the said curved edge being so proportioned as

to cooperate with the step or projection of the key bit immediately above the projection on said bit which engages the shouldered recess 45 in the tumbler. The forward end of the catch 50 is forked or bifurcated to straddle the upstanding lug 46 on the tumbler, and on the inner arm 52 of the fork there is formed a detent or projection 53 forming rightangled shoulders with the adjacent edges of the jaw 52 and having its outer face inclined or chamfered, as shown in Fig. 5, the parts being so constructed and arranged that the lug 46 on the tumbler will be engaged with one side or the other of the detent 53 on the catch and serve to hold the tumbler in its extreme adjustments in either direction. As shown in Fig. 5, the tumbler is positively held by the catch in the adjustment of the tumbler to effect the unlocking movement of the bolt, thereby preventing the operation of the latch except by means of a specially fashioned key fitting the lock. When the tumbler occupies its other position of adjustment, the lug 46 on the tumbler is in engagement with the opposite side of the detent 53 on the catch with the curved surface of the lug partially in engagement with the inclined surface of the detent, so that a sliding movement imparted to the tumbler will not be materially resisted by the engagement between the lug on the tumbler and the detent on the catch, thereby materially facilitating the operation of the tumbler when the bag is being locked.

Secured to the pivotal end of the catch 50 is a spring 55, the other end of which engages the inner wall of the auxiliary casing 30, said spring serving to swing the catch 50 on its pivot, so as to cause the detent 53 to engage the lug 46 on the tumbler at all times, except when the catch is moved by the key in opposition to the tension of the spring.

The latch 20, the finger piece 23 and the auxiliary casing and the elements carried by the latter reciprocate or slide in the casing as a unit and are normally supported by helical springs 56 surrounding the guide pins 16, so that the hasp engaging lugs 22 on the latch are maintained normally in the path of movement of the hasp members on the cooperating member of the bag frame. To open the bag, it is only necessary to depress the finger piece 23 which forces the latch 20 and the parts carried thereby downward until the lugs 22 pass out of engagement with the hasp members. When the finger piece is released, the latch immediately resumes its normal position, as shown in Fig. 2, and when the bag is closed, the hasp members engaging the rounded front edges of the lugs 22 force the latch toward the bottom of the casing against the tension of the springs 56, and when the openings in the hasp members have passed into registry with the lugs 22, the springs immediately

move the latch member upward, thereby latching the two jaw members of the bag frame together in closed position, but permitting the said jaw members to be opened 5 or separated by merely depressing the finger piece, as will be understood. In order to positively lock the jaw members of the frame together, there is provided a sliding bolt 60, which may conveniently take the 10 form shown in Fig. 6, comprising a base section 64 slotted, as at 65, to receive the key pin 26, a vertical yoke-like member 61 and two winged sections provided with upstanding lugs 62 and 63, the bolt being recessed 15 or cut away on each side of the yoke-like section 61 to provide openings 66—66 which are engaged by the lugs 42 on the tumbler, so that the sliding movement of the tumbler effected by the turning of the key, will produce 20 a corresponding sliding movement of the bolt 60, such sliding movement of the bolt being permitted by the recessed front edge of the auxiliary casing 30. The vertical elements of the bolt are in sliding contact 25 with the inner face of the front wall of the main casing 10, so that when the bolt is moved in one direction, the lug 62 will move into registry with a recess or notch 28 formed in one end of the forward edge 30 of the latch plate 20 and the lug 63 will pass into registry with the cut away front edge 29 of the latch plate, between which and the inner face of the frontwall of the casing, the yoke-like member 61 slides, and 35 the two lugs 62 and 63 will not interfere with the normal sliding movement of the latch.

To lock the bag, the key, having an appropriately fashioned bit, is inserted through the key hole 27 and guided to its operating seat in the lock on the key pin 26 which passes up into the hollow barrel of the key. Preferably the key hole slot is so formed that the key may be inserted with the bit extending in either direction, as indicated in Fig. 1.

45 After the key has been seated, it is given a partial turn to cause the bit to engage the front curved edge 51 of the catch 50 and swing the catch on its pivot to disengage the detent 53 from lug 46 on the tumbler 40, permitting the latter to be advanced by the lower element of the key bit, which engages the shoulder 45 next adjacent the lug 46 on the tumbler, the continued rotary movement of the key slides the tumbler 50 along the upper surface of the bottom of the auxiliary casing 30, the tumbler carrying with it, in its sliding movement, the bolt 60 until the lugs or projections 62 and 63 move out of registry with the slotted or 55 cut away portions 28 and 29 of the latch 20 and move directly under the portions of the latch adjacent the lugs 22—22, thereby preventing any movement of the latch in the casing. The completion of the locking 60 operation will leave the parts in the re-

lative position shown in Fig. 5 with the catch 50, now free from engagement with the key bit, moved inwardly by the spring 55, so that the detent 53 drops behind the squared shoulder of the lug 46 and thereby 70 locks the tumbler in its adjusted position and prevents the movement of the tumbler until the catch 50 shall have been again swung outwardly on its pivot by the key to disengage the detent 53 and lug 46. When 75 it is desired to unlock the bag, the key is inserted as before and turned in the opposite direction which will have the effect of first moving the catch 50 on its pivot to release the detent 53 from engagement with the lug 80 46 on the tumbler, the lower member of the key bit will engage the shouldered recess 45 of the tumbler and move the latter and the bolt 60 in the reverse direction to bring the lugs 62 and 63 of the bolt into registry 85 with the recessed or cut away portions 28 and 29 of the latch 20, so that the latter may be operated by the finger piece 23, as hereinbefore described, to disengage the locking lugs 22 from the hasp members 3. 90

While the lock has been illustrated with a single catch 50 for locking the tumbler 40, it will be obvious that a series of superposed catch members having the key engaging faces 51 thereof arranged in stepped or overchanging relation to cooperate with a corresponding series of steps on the key bit, so that the several latch members will have to be swung simultaneously on the pin 35 upon which they are pivoted, to disengage the several detents 53 on the catch members from the lugs 46 on the tumbler 40. Ordinarily, however, a single catch will prove effective, as the particular disposition of the key engaging surfaces of the catch and of the tumbler may be such as to adapt the lock to a relatively wide range of keys or key bits, each lock being operable only by its particular key and no other. 100

46 What I claim is:

1. A bag lock comprising a casing, a latch 115 slideable in the casing and having means for engaging a hasp, a bolt slideable longitudinally in the casing and having means cooperating with the latch to hold the latter against sliding movement, a tumbler slideably supported on said latch and engaging the bolt to shift the latter, and a tumbler catch mounted on the latch and cooperating with the tumbler to lock the latter, the tumbler and catch having key engaging surfaces so arranged as to require the catch to be released before the tumbler can be shifted. 120

2. A bag lock comprising a casing, a latch 125 slideable in the casing and having means for engaging a hasp, a bolt slideable longitudinally in the casing and having means cooperating with the latch to hold the latter against sliding movement, a tumbler slideably supported on said latch and engaging 130

the bolt to shift the latter, and a spring pressed tumbler catch mounted on the latch and cooperating with the tumbler to lock the latter, the tumbler and catch having key 5 engaging surfaces so arranged as to require the catch to be released before the tumbler can be shifted.

3. A bag lock comprising a casing, a latch 10 slideable in the casing and having means for engaging a hasp, a bolt slideable longitudinally in the casing and having means cooperating with the latch to hold the latter against sliding movement, a tumbler slidably supported on said latch and engaging the bolt 15 to shift the latter, and a spring pressed tumbler catch pivotally mounted on the latch and cooperating with the tumbler to lock the latter, the tumbler and catch having key 20 engaging surfaces so arranged as to require the catch to be released before the tumbler can be shifted.

4. A bag lock comprising a casing, a hasp 25 engaging latch slideable in the casing, pins secured in the casing for guiding the latch, springs on said pins normally holding the latch in hasp engaging position, a finger piece for depressing the latch, a bolt slideable longitudinally in the casing and having means 30 cooperating with the latch to hold the latter against sliding movement, a tumbler slidably supported on said latch and engaging the bolt to shift the latter, and a tumbler catch mounted on the latch and cooperating with the tumbler to 35 lock the latter, the tumbler and catch having key engaging surfaces so arranged as

to require the catch to be released before the tumbler can be shifted.

5. A bag lock comprising a casing, a 40 spring supported hasp engaging latch in said casing, a sliding bolt cooperating with the latch to hold the same against movement, a tumbler slideable on said latch and engaging the bolt to move the same into operative and inoperative positions, and a catch pivoted on the latch serving to lock the tumbler in its locking position, the tumbler and catch having key engaging surfaces 45 so arranged as to require the catch to be released before the tumbler can be shifted to unlocking position.

6. A bag lock comprising a casing, a latch 50 plate having hasp engaging lugs slidably mounted in said casing, a finger piece projecting from said latch plate and containing a key hole, a bolt slideable longitudinally of the casing and having lugs thereon adapted to be moved into and out of engagement with said latch plate, a second 55 plate supported by the latch plate, a tumbler slideably mounted on said second plate and having means engaging the bolt to effect conjoint movement of the bolt and tumbler, and a catch pivotally mounted on the second plate and cooperating with the tumbler to hold the same against unlocking movement, the tumbler and catch having key engaging surfaces 60 so arranged as to require the catch to be released before the tumbler can be shifted to unlocking position.

In testimony whereof I affix my signature.

DANIEL E. SEDLACK.
